CLAIM

The ornamental design for a teardrop shaped mailbox, as shown and described.

DESCRIPTION

FIG. 1 is a top perspective view of a teardrop shaped mailbox, showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof.

FIG. 7 is a top plan view thereof; and,

FIG. 8 is a bottom plan view thereof.

Broken lines are included for depicting environmental subject matter and form no part of the claimed design.

1 Claim, 6 Drawing Sheets(56)
